US00D609255S

(12) **United States Design Patent**
Bare et al.

(10) **Patent No.:** US D609,255 S
(45) **Date of Patent:** ** Feb. 2, 2010

(54) **MIXING PADDLE**

(75) Inventors: **Rex O. Bare**, Lake Forest, CA (US);
Jeffrey C. Smith, Costa Mesa, CA (US)

(73) Assignee: **IBIS Biosciences, Inc.**, Carlsbad, CA
(US)

(**) Term: **14 Years**

(21) Appl. No.: **29/328,150**

(22) Filed: **Nov. 19, 2008**

(51) **LOC (9) Cl.** 15-09

(52) **U.S. Cl.** D15/138

(58) **Field of Classification Search** D7/379,
D7/412; D8/19; D15/138, 139, 140; D23/200;
D24/220; 7/105, 151; 366/143, 149, 168.1,
366/192, 279, 309, 312, 325.92, 326.1; 416/71
See application file for complete search history.
